UNITED STATES PATENT OFFICE

171,244

PORTABLE HOUSE

Carl V. Bergstrom, Santa Clara, Calif.

Application June 18, 1952, Serial No. 20,249

Term of patent 14 years

(Cl. D13—1)

To all whom it may concern:

Be it known that I, Carl V. Bergstrom, a citizen of the United States, residing at Santa Clara, State of California, have invented a new, original, and ornamental Design for a Portable House, of which the following is a specification, reference being had to the accompanying drawing, forming a part hereof.

Fig. 1 is a perspective view of the portable house, showing the front and one end of my new design;

Fig. 2 is a perspective view of the portable house showing the back and the other end of my new design.

The dominant features of my design reside in the portions shown in full lines.

I claim:

The ornamental design for a portable house, as shown and described.

CARL V. BERGSTROM.
